(57) **CLAIM**

The ornamental design for a rifle component, as shown and described.

DESCRIPTION

FIG. 1 is a perspective view of an embodiment of a rifle component showing my new design;

FIG. 2 is a top plan view thereof;

FIG. 3 is bottom plan view thereof;

FIG. 4 is a left side elevational view thereof;

FIG. 5 is a right side elevational view thereof;

FIG. 6 is a rear elevational view thereof; and,

FIG. 7 is a front elevational view thereof.

The broken away symbols in the drawings views 1 through 7 indicate the appearance of any portion of the rifle component between the break lines forms no part of the claimed design. The broken lines shown in the drawings are for environmental purposes only and form no part of the claimed design.
